CHARLES HARDY, OF NEW YORK, N. Y., ASSIGNOR TO AMSCO PRODUCTS, INC., OF NEW YORK, N. Y., A CORPORATION OF NEW YORK.

MULTIPLE VARIABLE AIR CONDENSER.

Application filed May 1, 1926. Serial No. 105,959.

This invention relates to electrical condensers, and more particularly to variable air condensers; and has special reference to the provision of an improved variable air condenser of the multi-unit type designed for use in tuned radio receiving circuits for producing a uni-control or simultaneous adjustment of successive or cascaded circuits.

As is well known, for simultaneously adjusting the oscillation constants of cascaded radio frequency circuits for tuning the same in unison and to the frequency of the received wave, it is the practice to mechanically couple the tuning control devices, such for example as the tuning condensers or inductances in the circuits, so that these may be adjustable by the manipulation of a single control dial. Where condensers are employed as the tuning devices, the desired results are generally accomplished either by mechanically coupling the rotor shafts of separate condensers or by building the condenser units in a single assembly with the rotors of the units mounted on a single shaft. In either form of construction it is an important desideratum to balance and equalize the tuning devices with great precision and accuracy throughout the whole tuning range so that the oscillation constants of the cascaded circuits may be adjusted to the same value with optimum precision throughout the wave length range for which the system is tunable.

To equalize the tuning operations, the condensers must be carefully matched or balanced so that the calibration curves of the same, especially when the condensers are in connected circuit arrangement, are substantially identical. Considerable difficulty has been experienced in producing an exact match or equalization of the condenser units to meet the usual service requirements, in spite of the fact that the condensers are capable of being standardized and built with sufficient precision by present manufacturing methods. It has been found, for example, that even though the condenser units which are coupled together for simultaneous adjustment or uni-control are adjusted and assembled by the manufacturer so that a balance is obtained, the balance or equalization of the condenser units will not be maintained under service conditions, due

generally to a structural instability of the condenser assembly. I have found that such instability arises from inherent mechanical forces and stresses active on the condenser parts to alter or distort the same and vary the capacities of the respective condenser units, especially when such condenser units are built or stacked up in a single assembly. I have further found that these forces and stresses may be mechanically balanced and counteracted so that the structural instability of the built-up assembly is effectively inhibited, so much so that the condenser units when once matched or balanced by the manufacturer will remain and will be maintained in balanced relation in normal use, even for an extended period of time.

The prime desideratum of my present invention therefore comprehends the provision of a multiple variable condenser in which the aforesaid disadvantages incident to condensers of prior manufacture are overcome and in which means are provided for counteracting or neutralizing such forces and stresses which have been found to produce distorting tendencies and consequent structural and electrical instability of the condenser.

To the accomplishment of the foregoing and such other objects as will hereinafter appear, my invention consists in the elements and their relation one to the other, as hereinafter more particularly described and sought to be defined in the claims; reference being had to the accompanying drawings which show the preferred embodiments of my invention, and in which:

Fig. 1 is a side elevational view of one form of multiple variable air condenser with parts broken away and showing my invention applied thereto.

Fig. 2 is a rear end elevational view thereof.

Fig. 3 is a view thereof taken in cross-section in the plane of the line 3—3, Fig. 1.

Fig. 4 is a vertical elevational view of a modified form of multiple condenser showing my invention applied thereto, and

Fig. 5 is a view thereof taken in cross-section in the plane of the line 5—5, Fig. 4.

Referring now more in detail to the drawings and having reference first to Figs. 1 to 3 thereof, I show a multiple variable air condenser comprising a frame structure gen-

erally designated as F and a plurality of condenser units generally designated as C', C² and C³ mounted in built-up or stacked relation on the frame structure F, each of 5 the condenser units including a stator and a rotor plate set designated respectively by s and r with an exponent corresponding to the condenser unit of which it forms a part.

The frame structure F comprises the opposite metallic end plates 10 and 11 connected by longitudinal members 12-15 to form a rectangular supporting framework. Each of the connecting members, and typically the connecting member 15, comprises a rod 15 threaded at its opposite ends 15² and 15³ for reception of the securing nuts 16, 16, spring washers 17, 17 being preferably interposed between the securing nuts and the end plates. The other connecting members 20 12-14 embody similar parts which are designated by corresponding and similar reference characters. Where the condenser embodies triple condenser units the frame F preferably further includes a backing or 25 supporting plate 18 to which the end plates 10 and 11 are joined by means of the angle brackets 19 and 20 secured to the backing plate 18 by means of the attaching elements 21, 21, the said angle brackets being joined 30 to the end plates 10 and 11 by attachment to the connecting rods 14 and 15, as clearly shown in the drawings.

The rotor plate sets r', r² and r³ each comprises a plurality of condenser plates 22, 22 35 all affixed in spaced relation to a single rotor shaft 23, which shaft is journaled for rotation in the end plates 10 and 11 of the frame F. In the preferred construction the plates are secured to the rotor shaft in a 40 manner disclosed in my copending application to electrical condenser manufacture, Serial No. 74,471, filed Dec. 10, 1925.

The stator plate sets s', s² and s³ each comprises a plurality of condenser plates 24, 24 45 arranged in interleaving relation with the stator plates 22, 22, the stator plates of the stator units s', s² and s³ being carried respectively by the posts 25, 26 and 27, which are insulatably mounted from each other 50 and from the frame F. For insulatably mounting the stators on the frame, there are provided at each end of the condenser assembly a plurality of insulating members 28, 28, which in the preferred construction 55 comprises tubular units, as clearly shown in Fig. 1 of the drawings, one end of the tubular units being seated in cup-shaped elements 29, 29 eyeleted or riveted to the end plates, the other end of each of the tubular 60 units being provided with a flanged cap 30 centrally apertured to receive a stud portion 31 integral with the stator supporting posts such as the post 27 illustrated in Fig. 1 of the drawings, this construction being 65 provided so that the stator units may be

mounted during assembly on the insulating pieces to interlock with the same without the use or employment of securing elements.

The stator plate sets s', s² and s³ are insulatably supported from each other by 70 means which include elements interposed between the stator plate sets and effective for mutually supporting one plate set longitudinally on the other, such means comprising the insulating members 32, 32 interposed between the adjacent ends of the stator posts 25-27, and in the preferred construction each of the insulating members is recessed at the opposite ends thereof for receiving the contiguous ends of the stator posts. In 75 the preferred construction each of these insulating members comprises a tubular unit as shown in Fig. 1 of the drawings, each end of which receives a pin or stud portion 33 integral with a stator post, a flanged or 80 cup-shaped recessed element 34 being received by the stud portion and interposed so as to seat the end of its tubular unit 32. With this construction it will be seen that the stator units may be stacked up or built 85 in longitudinal alignment and may be assembled one with respect to the other by merely interlocking the insulating members with the stator supporting posts, the assembling of the parts being obtained with 90 facility and without the use of securing elements such as screws or bolts.

This multiple condenser assembly is particularly designed for use in radio receiving 100 circuits as a uni-tuning control for the cascaded radio frequency circuits thereof, and as heretofore explained, the rotor and stator components of the condenser units must be carefully balanced and mechanically matched so that the capacities thereof may 105 be equalized over the whole tuning range of the radio receiving set. As heretofore stated, it has been found that even though the condenser units are adjusted and assembled by the manufacturer so that a balance 110 is obtained, the balance or equalization of the condenser units will be disturbed under service conditions. I have found that 115 this is due generally to a structural instability of the condenser assembly. I have found more particularly that such instability arises from inherent mechanical forces and stresses active on the condenser parts to alter or distort the same and vary the capacities of the respective condenser units. 120 More specifically, in the construction exemplified in Figs. 1 to 3 of the drawings, when the condenser stators are built in stacked-up relation the compressive forces exerted by the end plates 10 and 11 on the stator supporting elements and the gravitational effect 125 on the stator parts both tend to distort or alter the position of the stator posts and the insulating members interposed therebetween, this resulting in moving the stator 130

and rotor plates out of true parallel relation, the uneven distortion producing an undesirable mis-matching of the condenser units.

I have found that these compressive and gravitational forces and stresses may be effectively compensated for and counteracted so that the built-up assembly is rendered stable, the stability being such that the integrity of the equalization of the condensers can be effectively maintained under normal service conditions. To accomplish the desired results, I provide means for transversely supporting the stators in a region intermediate the end plates of the condensers and preferably such means is designed and constructed to support the stators on the condenser frame to produce a transverse mutual support for the frame and stator parts.

More specifically, such means comprises the plate-shaped members 35, 35 arranged intermediate adjacent condenser units such as the units C' and C² or C² and C³, said plate-shaped members connecting so as to mechanically join together for transverse support the frame members 12-15 with the interposed stator supporting elements 32, 32, the construction being such that the stator supporting elements and the stator units supported thereby are held against transverse displacement in regions intermediate the end plates 10 and 11 of the frame F. The plate-shaped members 35, 35 are fixed to the frame members 12-15 so as to mutually support one frame member with respect to the other transversely, and are connected to the interposed stator supporting elements 32, 32 to support the latter transversely but not longitudinally so that relative longitudinal movement is permitted while transverse movement is prevented, this affording greater facility in assembling the parts and permitting differential expansion and contraction in a longitudinal direction between the parts.

Structurally each of the plate-shaped members 35 is fixed to a plurality of frame members, the same being provided with terminal apertures 35', 35', (Fig. 3) received by the connecting frame rods 12-15 and with central orifices 35² received by the interposed insulating elements 32, 32, the members 35, 35 being fixed to the frame rods 12-15 by being held between spacing sleeves 36, 36 on the frame rods 12-15. The orifices 35² define walls which snugly embrace the insulating elements or members 32 so that these are effectively supported transversely of the frame, the insulating elements 32 being, however, capable of longitudinal movement in the members 35 for the purpose specified.

By means of this construction I not only accomplish the important results of transversely joining the stators to the condenser

frame at intermediate regions and to strengthen the connecting frame members at such regions, but I am enabled to provide an assembly in which the compressive stresses exerted on the aligned stator posts 25-27 by 70 the end plates are effectively minimized or eliminated, such compressive stresses being wholly undesirable in a condenser assembly. It will be seen, moreover, that the mechanism provided is comparatively simple and 75 is so designed as to permit the ease of assembling of the condenser parts which characterizes the condenser construction.

Referring now to Figs. 4 and 5 of the drawings, I show my invention applied in its 80 preferred form to a double condenser of the straight-line frequency type, such condenser differing from that shown in Figs. 1-3 of the drawings principally by the shape of the plates and the manner of supporting the 85 stator in the condenser frame. The parts, otherwise similar, are designated by similar reference characters.

In the modified form of the invention as shown in Figs. 4 and 5, the plates 10 and 11 90 of the frame F are connected together by means of three frame rods 37, 38 and 39 having the spacing sleeves 40, 40 thereon, the supporting posts 25 and 26 for the stators s' and s² being arranged in a longitudinal 95 plane intersecting the longitudinal plane passing through the connecting rods 37 and 38, as clearly shown in Fig. 5 of the drawings. For transversely supporting the stator insulating elements 32, 32 (two in number) 100 on the frame members 37 and 38, I preferably provide a single plate-shaped member 41 arranged intermediate the condenser units C' and C², the said plate-shaped member 41 being fixed to the frame rods 37-39 between 105 the spacing sleeves 40 and being recessed at 42, 42 for slidably yet snugly receiving the insulating members or elements 32, 32 in a manner similar to that described in connection with Figs. 1-3 of the drawings. In this 110 modified form of the invention, the plates of the rotor units r' and r² may be connected together by means of a strap or connecting plate 43 which bridges the member 41.

The manner of assembling and using the 115 multiple variable air condenser of my present invention and the advantages thereof will in the main be fully apparent from the above detailed description and operation thereof. It will be further apparent that while I have 120 shown and described my invention in the preferred forms, many changes and modifications may be made in the construction disclosed without departing from the spirit of the invention, defined in the following 125 claims.

I claim:

1. A multiple variable condenser comprising a frame having end plates and members connecting the end plates, a rotor journaled 130

- in said frame and having a plurality of rotor plate sets, a stator mounted in said frame and having a plurality of stator plate sets arranged to interleave with the rotor plate sets to form therewith a plurality of condenser units, means for insulating the stator plate sets from each other including elements interposed between the said stator plate sets and mutually supporting one plate set longitudinally on the other, and means arranged intermediate the condenser units connecting so as to mechanically join together the frame members with said interposed stator supporting elements for transversely supporting the frame and the stator in a region intermediate the end plates. 70
2. A multiple variable condenser comprising a frame having end plates and members connecting the end plates, a rotor journalled in said frame and having a plurality of rotor plate sets, a stator mounted in said frame and having a plurality of stator plate sets arranged to interleave with the rotor plate sets to form therewith a plurality of condenser units, means for insulating the stator plate sets from each other including elements interposed between the said stator plate sets and mutually supporting one plate set longitudinally on the other, and means arranged intermediate the condenser units connecting so as to mechanically join together a plurality of the frame members with an interposed stator supporting element for transversely supporting the stator on the frame and one frame member on the other in a region intermediate the end plates. 90
3. A multiple variable condenser comprising a frame having end plates and members connecting the end plates, a rotor journalled in said frame and having a plurality of rotor plate sets, a stator mounted in said frame and having a plurality of stator plate sets arranged to interleave with the rotor plate sets to form therewith a plurality of condenser units, elements interposed between the said stator plate sets and mutually supporting one plate set longitudinally on the other, and means arranged intermediate the condenser units connecting so as to mechanically join the frame members with said interposed stator supporting elements for transversely supporting the frame and the stator in a region intermediate the end plates. 100
4. A multiple variable condenser comprising a frame having end plates and members connecting the end plates, a rotor journalled in said frame and having a plurality of rotor plate sets, a stator mounted in said frame and having a plurality of stator plate sets arranged to interleave with the rotor plate sets to form therewith a plurality of condenser units, elements interposed between the said stator plate sets and mutually supporting one plate set longitudinally on the other, and means arranged intermediate the condenser units connecting so as to mechanically join the frame members with said interposed stator supporting elements for transversely supporting the frame and the stator in a region intermediate the end plates. 110
5. A multiple variable condenser comprising a frame having metallic end plates and members connecting the end plates, a rotor journalled in and conductively connected to said frame and having a plurality of rotor plate sets, a stator insulatably mounted in said frame and having a plurality of stator plate sets arranged to interleave with the rotor plate sets to form therewith a plurality of condenser units, means for insulating the stator plate sets from each other including insulating elements interposed between the said stator plate sets and mutually supporting one plate set longitudinally on the other, and means arranged intermediate the condenser units mechanically joining a plurality of frame members together and to said interposed stator supporting insulating elements for transversely and mutually supporting the frame members and the stator in a region intermediate the end plates. 120
6. A multiple variable condenser comprising a frame having end plates and members connecting the end plates, a rotor journalled in said frame and having a plurality of rotor plate sets, a stator mounted in said frame and having a plurality of stator plate sets arranged to interleave with the rotor plate sets to form therewith a plurality of condenser units, elements interposed between the said stator plate sets and mutually supporting one plate set longitudinally on the other, and a means fixed to and transversely joining the frame members at a region intermediate the condenser units, said means embracing an interposed stator supporting element for supporting the same transversely on the frame members. 130
7. A multiple variable condenser comprising a frame having end plates and members connecting the end plates, a rotor journalled in said frame and having a plurality of rotor plate sets, a stator mounted in said frame and having a plurality of stator plate sets arranged to interleave with the rotor plate sets to form therewith a plurality of condenser units, elements interposed between the said stator plate sets and mutually supporting one plate set longitudinally on the other, a plurality of said frame members each including a rod and spacing sleeves thereon, and a plate shaped means fixed to the frame members between the spacing sleeves thereof and transversely joining the frame members for mutual support, the said 125

plate shaped means having an orifice supportingly receiving a stator supporting element.

8. A multiple variable condenser comprising a frame having metallic end plates and a plurality of members connecting the end plates, a rotor conductively journaled in said frame and having a plurality of rotor plate sets, a stator insulatably mounted in said frame and having a plurality of stator plate sets arranged to interleave with the rotor plate sets to form therewith a plurality of condenser units, insulating elements interposed between the said stator plate sets and mutually supporting one plate set longitudinally on the other, the said frame members each including a connecting rod and spacing sleeves thereon, and plate shaped means fixed to a plurality of said rods between the spacing sleeves thereof for transversely joining the frame members for mutual support, the said plate shaped means having an orifice receiving an insulating element for transversely supporting the same and the stator on the frame members.

9. A multiple variable condenser comprising a rotor plate set, metallic end supporting plates conductively integral therewith, members connecting the end supporting plates, a plurality of stator plate sets, means for supporting the stator plate sets insulated from each other and from the end supporting plates, said means consisting of a plurality of posts carrying each stator plate set, insulating members arranged between the posts of the stator plate sets and insulating pieces arranged between the end supporting plates and the adjacent ends of the said posts of the stator plate sets, and means arranged intermediate the stator plate sets connecting so as to mechanically join together a plurality of the said members with the said insulating members for providing mutual transverse support between the stator plate sets and the said members.

Signed at New York city in the county of New York and State of New York this 23rd day of April A. D. 1926.

CHARLES HARDY.
